UNITED STATES PATENT OFFICE.

WILLIAM P. ORTH, OF MILWAUKEE, WISCONSIN.

WINDOW FRAME.

Application filed January 6, 1927. Serial No. 159,355.

The invention relates to window frames and more particularly to those of knock-down construction.

Window frames are frequently distributed and sold in knock-down condition to facilitate shipment and storage, and are required to be assembled before use. As assembling is sometimes done hastily and carelessly in the field, the various parts may not be accurately fitted together, thereby detracting from the appearance of the frame and sometimes preventing proper fitting of the sash.

It is an object of the present invention to provide a knock-down window frame which can be accurately and quickly assembled to present a workmanlike appearance and to insure proper fitting of the sash.

Another object of the invention is to provide a window frame which is weather-tight and in which the side jambs may be used interchangeably as mullion jambs without alteration.

A further object is to perfect details of construction generally and to effect economies in manufacture.

The invention further consists in the several features hereinafter set forth and more particularly defined by the annexed claims.

In the accompanying drawings, Fig. 1 is an outside elevation of a window frame embodying the invention;

Fig. 2 is an inside elevation thereof on a larger scale;

Fig. 3 is a detail sectional view taken on the line 3—3 of Fig. 2;

Fig. 4 is a detail sectional view taken on the line 4—4 of Fig. 2; and

Fig. 5 is a detail transverse sectional view taken through one of the side jambs.

In these drawings, the numeral 10 designates spaced side jambs, each provided at both ends with a tongue 11 formed by rabbeting. The upper tongued ends of the side jambs 10 are let into grooves or dadoes 12 extending transversely across the lower face of a head jamb 13, and the lower tongued ends of the jambs are let into transverse grooves 14 formed in the upper face of a sill 15, the grooves 14 extending to the rear edge 50 of the sill but terminating some distance short of the forward edge. The ends of the head jamb 13 and sill 15 project some distance beyond the side jambs, so that vertically disposed boards 16 parallel to the side jambs may be nailed against these ends to form boxes for sash weights 17, as seen in

Figs. 2 and 5. The side jambs 10 extend integrally from edge to edge and both have their forward edges provided with full length tongues 18, formed by rabbeting, to enter and snugly fit within longitudinal grooves 19 on the inner faces of side casings 20. The side casings 20 abut at their lower ends against the outer projecting portions or horns of the sill 15, and the upper ends of the side casings extend above the head jamb 13 to be flush with the upper edge of a head casing 21. The head jamb 13 is also provided with a tongue 22 at its forward edge to enter a horizontal groove 23 extending longitudinally of the head casing 21 near its lower edge. The upper edge of the head casing 21 and the upper ends of the side casing 20 flush therewith are surmounted by a rabbeted head casing cap 24, preferably provided with a water drip groove 25 in its forward under face. The extension of the side casings to the upper edge of the head casing serves to reinforce the latter against lateral binding or breakage after the head casing cap is in place.

The inner faces of the side jambs 10 and the head jamb 13 are provided with grooves 26 and 27, respectively, to receive parting stops 28, and are also provided near their forward edges with shallow rabbets 29 to receive blind stops 30 spaced forwardly from the parting stops. The parting stops 28 and blind stops 30 are each of the same rectangular cross-section, as seen in Figs. 3 and 5, the parting stops 28 being inserted on edge while the blind stops 30 rest on one face.

The lower face of the sill 15 is provided with a longitudinal groove 31 for receiving the sheathing of the building and a drip groove 32 is formed near the forward edge of the sill. The usual interior trim 33 is subsequently secured to the side and head jambs and the sill after the window frame is mounted in place in a building wall.

In assembling the window frame of this invention, the interfitting of the several parts of the frame determines their proper mutual alignment. The side and head jambs and the sill may be first temporarily fitted together, following which the tongues at the forward edges of the side and head jambs are pressed into the corresponding grooves of the side and head casings. This at once determines the proper and accurate relation of these parts. The parts may then be per-

manently secured together by nails or screws, as the case may be, and to firmly secure the lower ends of the side jambs in the sill, cleats 34 are provided to abut against the 5 sill and the adjacent outer faces of the side jambs and to receive nails entering both the side jambs and the sill, as indicated in Fig. 2. The head casing cap 24 is then secured in abutment with the upper edge of the head 10 casing and the upper ends of the side casings. The frame is then ready to receive the sashes 35 and be incorporated in a building wall in the usual manner.

In the case of a mullioned frame, the sill 15 and head jamb are each formed in one piece and provided with intermediate transverse grooves to receive the mullion jambs, which are identical with the side jambs 10 and interchangeable therewith without alteration. In this manner, manufacturing operations are simplified and fewer parts need be carried in stock by the distributor. As the parting stops and blind stops are of identical cross-section this also facilitates 25 manufacture. The interfitting of the several parts of the frame serves to permit convenient, accurate and inexpensive assembly and also serves to afford weather-tightness, which is of importance in window frame 30 construction. By simple alterations, chiefly the addition of molding strips to the head and side casing jambs, or the narrowing of the side and head casings, or both, it is possible to convert the frame for use with brick, 35 brick veneer, concrete, stucco, or tile walls, as conditions require. In the case of masonry construction, the side pieces 16 shown in Fig. 2 are of particular value in conveniently forming the sash weight boxes.

40 What I claim as new and desire to secure by Letters Patent is:

1. In a window frame, the combination of a sill, spaced side jambs secured to said sill, a head jamb secured to said side jambs, 45 said side jambs and head jamb having projecting tongues at their forward edges, and side and head casings having grooves on their inner faces forming a continuous channel receiving the tongues on said side and head jambs for securing the interalignment of said parts and for effecting a weather-tight seal and blind stops secured to the inner faces of said side and head jambs.

2. In a window frame, the combination

of a sill having spaced transverse grooves 55 on its upper face, a head jamb having spaced transverse grooves on its lower face and a longitudinally extending tongue on its forward edge, a pair of side jambs having tongues at each end adapted to enter and fit 60 within said grooves in said sill and said head jamb, said side jambs also having longitudinal tongues at their forward edges, and side and head casings having communicating grooves on their inner faces adjacent 65 their inner edges adapted to receive said tongues on said head and side jambs for securing the interalignment of said parts and effecting a weather-tight seal, and blind stops secured to the inner faces of said side 70 and head jambs.

3. In a window frame, the combination of a sill having transverse jamb-receiving grooves on its upper face, side jambs having their lower ends adapted to enter said 75 grooves, and cleats secured transversely to the outer faces of said side jambs adjacent the lower ends thereof and adapted for nailing against the upper face of said sill to secure said jambs to said sill. 80

4. In a window frame, the combination of a sill, spaced side jambs secured to said sill, a head jamb secured to said side jambs, said side jambs and head jamb having projecting tongues at their forward edges, 85 and having aligned rabbets on their inner faces adjacent the tongued forward edges, blind stops secured in said rabbets, and side and head casings having communicating grooves on their inner faces receiving the 90 tongues of said side and head jambs for securing the interalignment of said parts and for effecting a weather-tight seal.

5. In a window frame, the combination of a sill having a transverse jamb-receiving 95 groove on its upper face, a side jamb having its lower end adapted to enter said groove, a cleat nailed transversely to the face of the side jamb opposite its sash-receiving portion and adjacent the lower end of said 100 jamb in position to subsequently abut against the upper face of said sill, and fastening nails passing vertically and diagonally through said cleat to enter said sill, said diagonally disposed nails also passing 105 through the lower end portions of said jamb.

In testimony whereof, I affix my signature.
WILLIAM P. ORTH.
